STUART DEAN, OF INDIANAPOLIS, INDIANA, ASSIGNOR TO DEAN BROTHERS COMPANY, OF INDIANAPOLIS, INDIANA, A CORPORATION.

VALVE CHEST.

Application filed May 14, 1927. Serial No. 191,476.

This invention relates to a valvechest for pumps and process of forming the same.

The chief object of the invention is to form a valvechest body with a plurality of chambers cross-connected with an intake port communicating with one of said chambers all without the use of cores or plugging and with the minimum amount of drilling.

The chief feature of the invention consists in the formation of a valvechest body having a plurality of chambers intercommunicating by a lateral channel, an intake to one chamber, and outlet from the other chamber, said chambers being separated by a partition with the included passages mentioned being formed as indicated.

Another chief feature of the invention consists of the process of forming a valvechest body of the character indicated.

The full nature of the invention will be understood from the accompanying drawings and the following description and claims.

In the drawings Fig. 1 is a perspective of one face of the pump body showing the intake passages and the cross-connecting channel. Fig. 2 is a perspective view of the opposite face showing the two valve chambers. Fig. 3 shows one step in the process of forming the pump body without the use of cores. Fig. 4 shows a similar view of a subsequent step in the process.

In the drawings 10 indicates a peripheral wall united by a partition 11 and having a base 12, thereby forming a pair of chambers 13 and 14. The base 12 is formed of sufficient thickness to include a lateral groove or recess 15 and an intake passage 16 is also provided. The valvechest body has a pair of parallel faces 17 and 18 so as to cooperate with suitable gasket means and other mechanism of a pump. Intake 16, by means of a drilled hole 19, communicates with chamber 13 and by the drilled hole 20, said chamber communicates with the passage 15 in turn communicating by drilled hole 21 with the chamber 14, said latter chamber having the discharge opening 22. In the chambers 14 and 13 the holes 21 and 19 are suitably faced as at 23 and 24 respectively. This facing is a bevel and forms a valve seat.

The action of the pump is as follows:

Thru suitable mechanism a valve controlling opening 19 is elevated from seat 24 and

air passes thru the intake 16 and the chamber 13. The air escapes therefrom when the valve is returned to the seat 24 and the valve controlling opening 21 is elevated from seat 23, and said air is discharged into chamber 14 where it is trapped therein by the valve returning to the seat 23 for subsequent discharge for example by way of the opening 22. The cycle is repeated for supplying air in chamber 13 and thence to chamber 14 as aforesaid. In order to mount the valvechest body, a centering portion 25 is provided and a pair of oppositely extending sockets 26 is also provided.

There is nothing new in the pump operation and the invention consists primarily in the valvechest body per se and the method of forming the same, which is as follows:

In Fig. 3, 27 indicates the match plate having the cope portion of the pattern 28 thereon and the flask portion 29, each being receivable by the cope 30 and drag 31 respectively, the whole being supported by the bottom board 32. Cope and drag are filled with green sand and the parting 33 is formed when the pattern is removed from the mold, leaving the respective outlines in the cope 30 and drag which the metal thereafter fills. The intake is formed by projection 34 of the green sand mold and the cross-connecting or lateral passage 15 is formed by the projection 35 of the green sand mold while the two chambers 14 and 13 are formed respectively by the projections 36 and 37 of the green sand mold, the latter being formed in the drag and the first being formed in the cope, as herein shown. When the casting is completed the passages 15 and 16 and chambers 14 and 13 are formed therein without the necessity of drilling and plugging, which heretofore has been the method of forming a valvechest body of this general character, or by coring to obtain said passages. After the casting has been formed, one of the faces 12 is ground flat on a grinder or lap wheel and then the casting can be machined upon its opposite face so that the two faces 17 and 18 are substantially parallel. After this has been performed, the casting can be placed in a jig, and the four holes 19, 20, 21 and 22 drilled individually or simultaneously and then the two holes 19 and 21 are beveled in the chambers 13 and 14 respectively, thereby

forming the valve seats 24 and 23 respectively and completing the formation of the valvechest body.

The invention claimed is:

- 5 1. A valve chest member for a pump including a pair of open-faced chambers in one face of the body and arranged in parallel relation with a common partition wall therebetween and integral with the body, another and elongated open-faced chamber forming a lateral passageway and in the opposite face of the body and extending transversely of the partition and terminating at opposite sides thereof, said body including a central, 10 chamber forming and separating wall with a pair of transverse passages therein, one for each of the first mentioned chambers and communicating with the elongated chamber forming passageway for cross connecting the

two first mentioned chambers, said wall having another pair of transverse passages therein, one for each of said first mentioned chambers, and a laterally directed open-faced passageway in the body face opposite the face including said two first mentioned chambers 25 and extending from one of the last mentioned passageways to the side of said body and forming a side opening therein.

2. A device as defined by claim 1 characterized by the termination of one of each of the central wall passageways in each chamber and communicating directly with the open-faced passageways, including a beveled seat opening into the communicating chamber.

In witness whereof, I have hereunto affixed my signature.

STUART DEAN.
